SUPPORT FOR MANIKINS

Erich Bloch, New York, N. Y.

Application February 3, 1951, Serial No. 209,259

5 Claims. (Cl. 223—120)

1

The present invention relates to devices of the type employed to support display figures, forms and models and particularly manikins.

For supporting such display devices as lay figures or manikins, it is customary to provide a large base plate with an exposed rod extending to an intermediate portion of the figure. A figure support device of this type is unsightly in appearance, detracts from the realism and ornamental semblance of the display and makes it difficult to apply a garment properly to the figure.

One object of the present invention is to provide a new and improved device for supporting a figure for display purposes, which is effective to uphold stably a display figure in natural attitude, which is unobtrusive when set up in operative position, so that it does not detract from the life-like, natural appearance of the figure, which can be easily and expeditiously applied to the feet or shoes of the figure without damage thereto, which can be easily and quickly fastened to a floor with minimum of defacement thereof and which is adjustable to fit feet or shoes of varying sizes and shapes.

Another object is to provide a figure supporting device which is comparatively simple and which can be inexpensively manufactured.

In accordance with certain features of the present invention, the figure support devices have clamp means by which the devices may be removably, adjustably and firmly attached to the feet or shoes, respectively, of the display figure or manikin and are adapted to be stably fastened to a floor to hold up the figure in display position. These support devices are constructed for attachment to the feet or shoes of the figure without mutilating them and in attached operative position have no connection to the figure except externally through the feet or shoes. After the support devices have been attached to the pedal extremities of the figure, it may be set up in proper display position by fastening these devices to a floor. In this fastened position, the support devices are almost unnoticeable, and consequently do not detract from the naturalness or realism of the figure.

Various other objects of the invention are apparent from the following particular description and from an inspection of the accompanying drawings, in which—

Fig. 1 is an elevation of a figure or manikin shown supported in display position by a form of support devices embodying the present invention;

2

Fig. 2 is a top plan view of a form of figure support device for the right shoe of the manikin, shown attached to the shoe and in floor fastened position;

5 Fig. 3 is a top plan view of the figure support device for the left shoe, shown in unattached position;

10 Fig. 4 is a top plan view of the figure support device for the right shoe, shown in unattached position and on a scale larger than that shown for the device in Fig. 3;

15 Fig. 5 is a side elevation of the figure support device shown in Fig. 4;

Referring to Figs. 1 to 5 of the drawings, the figure support device of the present invention is shown in position to hold up and sustain a manikin A in display position on a floor B. Two of such devices are shown, one for each shoe C of the manikin. Each of these devices comprises a thin flat base plate 10 shown in the form of a T and constituting a stem section 11 and a crosshead section 12 at one end of said stem section. This base plate 10 is adapted to be fastened to the floor and for that purpose has holes 13 for screws 14 as shown. These holes 13 are located at the outer end of the stem section of the base plate 10 and at the outer ends of the cross head section 12 of said base plate.

30 Shoe clamping means mounted on and secured to the base plate 10 comprise a pair of flat clamping arms 15 and 16 rigid with the base plate 10 and terminating at their outer ends in clamping hooks 17 and 18, respectively, for catch engagement with the projecting lip D of the sole on the inner side of the shoe, and a pair of flat clamping arms 19 and 20 adjustably supported on said base plate and terminating at their outer ends in clamping hooks 21 and 22, respectively, for engagement with the projecting lip 40 of the sole on the opposite side of the shoe. The clamping arms 15 and 16 are shown integral with and extending from the opposite sides of the crosshead plate section 12 in the same plane thereof and diverge outwardly from said sides. The clamping hooks 17 and 18 at the outer ends of these clamping arms 15 and 16, respectively, are U-shaped and are formed with substantially rectangular turns except for a slight flare in order to straddle conformably the usual substantially square projecting lip D of the shoe sole.

45 The adjustable clamping arms 19 and 20 form part of a substantially U-shaped slide bracket 24 having a base section 25 and the side arms 19 and 20. These side arms 19 and 20 diverge 55 from the base section 25 of the slide bracket

24, so that said slide bracket is almost in the form of a V with a broad base, and the clamping hooks 21 and 22 at the outer ends of said arms, respectively, are U-shaped with substantially rectangular turns except for a slight flare for straddling conformably the usual square projecting lip D of the shoe sole.

For securing the slide bracket 24 in the base plate 10 in adjusted position and to guide said bracket in its adjusting movement along said plate, the crosshead section 12 of said plate has an elongated slot 27 extending therealong and the slide bracket in its base section 25 carries a fastening member 28 shown in the form of a screw passing therethrough and through the slot. This screw 28, shown in the form of a machine screw or stud with a flat head 29, extends upwardly and is threaded into the base section 25 of the slide bracket 24. The longitudinal sides of the slot 27 may be provided with bevels 30 corresponding to the taper on the screw head 29 to permit said head to lie flush with the bottom surface of the base plate 10. If desired, instead of a machine screw 28, a bolt may be provided with a nut on top or bottom. In that case, the slot 27 may simply have parallel longitudinal sides.

The slide bracket 24 is not only adjustably movable along the crosshead plate section 12 according to the width of the shoe to which the device is to be attached, but is also rotatably adjustable along the axis of the fastening member 28 according to the shape of the shoe, as shown in Fig. 4.

The hook 17 is adapted to engage the inner side section of the shoe sole near its shank (i. e. the narrow part of the sole beneath the instep) and the hook 18 is adapted to engage the inner side section of the shoe sole near the toe, these two inner side sections in the conventional shoe being in a line extending substantially parallel to the longitudinal axis of the shoe. Consequently, the two clamping arms 15 and 16 carrying these hooks 17 and 18 are substantially of the same length and of the same inclination with respect to the crosshead section 12 of the base plate 10 to align these hooks in a direction substantially parallel to the side of the stem section 11 of the base plate 10. The hooks 17 and 18 are inclined along their bases or outer edges with respect to each other to conform with the contour of the side sections of the shoe sole where they catchably engage.

The hook 21 is adapted to engage the outer side section of the shoe sole near the shank and the hook 22 is adapted to engage the outer side section of the shoe sole near the toe, and these hooks are inclined along their bases or outer edges with respect to each other to conform with the contour of the side sections of the shoe sole where they catchably engage. Since the two sides of the sole of a conventional shoe are not symmetrical, the two outer side sections of the sole engaged by the hooks 21 and 22 are aligned in a direction inclined with respect to the longitudinal axis of the shoe. Therefore, the two clamping arms 19 and 20 carrying these hooks 21 and 22 are of different length, the arm 19 being the longer one, to conform generally with the contour of the outer side of the shoe sole. The rotatable adjustability of these clamping arms 19 and 20 accommodates for variations in this sole contour in different shoes.

The fixed location of the clamping arms 15 and 16 and the hooks 17 and 18 thereon, with respect

to the base plate 10, and the alignment of these hooks parallel to the side of the stem section 11 of the base plate 10 as described, will assure the location of the major length of the stem plate section centrally beneath the shoe in floor mounted position of the figure support device, as shown in Fig. 2. This stem plate section 11 is substantially rectangular and is narrower than the base section of the shoe, so that it will be almost concealed by the shoe in floor mounted position, except for its outer end section 35 which projects a short distance beyond the heel of the shoe sufficient to expose the hole 13 therein in accessible position for floor fastening.

15 The crosshead section 12 of the base plate 10 is long enough so that its outer end sections 36 project a short distance beyond the sides of the shoe sufficient to expose the holes 13 therein in accessible position for floor fastening.

20 Figs. 2, 4 and 5 show a support device for the right shoe of the manikin. Fig. 3 shows a support device which is similar except that it is reversed in construction for use in connection with the left shoe of the manikin. However, due to 25 the adjustable mounting of the bracket 24, the same support device may be employed for either shoe.

In the application of the support devices of the present invention, the figure to be placed on display, as for example the manikin, is dressed with shoes and the support devices attached thereto. The attachment is effected on each shoe by placing the appropriate right hand or left hand device underneath said shoe with the fixed clamping hooks 17 and 18 straddling and gripping the projecting lip D of the shoe sole on its inner side as shown in Fig. 2. The bracket 24 with its fastening screw 28 loose is then slid along the stem section 11 of the base plate 10 and rotated about the axis of said screw to cause the clamping hooks 21 and 22 on said bracket to straddle and grip the projecting lip of the shoe sole on its outer side as shown in Fig. 2. After the screw 28 is tightened to hold the bracket 24 in adjusted position, the manikin is set in the desired position and pose and the support devices secured to the floor by the screws 14 through the holes 13 in the base plate 10. If desired, nails may be employed instead of the screws 14.

40 As shown in Fig. 2, the support devices will be almost inconspicuous. Only the ends 36 of the crosshead section 12 of each base plate 10 will show, the projecting end 35 of the stem section of said base plate being behind the shoe and being almost concealed thereby. If desired, these 45 projecting end sections 35 and 36 of the base plate 10 may be concealed easily by a floor covering.

50 It should be noted in connection with the devices shown in Figs. 1 to 5, that these can be 60 simply and inexpensively constructed from sheet metal by cutting and stamping or bending operations.

65 Although the figure support devices of the present invention are particularly designed to be attached to figures fitted with shoes, as far as certain aspects of the invention are concerned, they may be applied to the feet of a figure or manikin not so fitted. In that case, the clamping hooks will have to be shaped accordingly to engage the sides of the foot. Therefore, in the following claims, by "foot" is intended to cover not only the terminal part of a leg when fitted with a shoe, but also when not so fitted.

70 75 Modifications of the embodiments shown with-

in the scope of the appended claims will readily occur to those skilled in the art. For example, while the clamping hooks are shown in pairs, two fixed and two adjustable, it is feasible to have three of the hooks fixed and one adjustable, and one or more of the fixed hooks may be pivotally mounted so as readily to adapt themselves to the contour of the foot or shoe sole.

What is claimed is:

1. A support device for a display figure having lower portions simulating human legs and feet and fitted with shoes, comprising a base plate adapted to extend along the underside of a shoe, a pair of clamping hooks rigid with said base plate and adapted to straddle the projecting lip of the sole of the shoe on one side thereof, a second pair of clamping hooks secured together as a unit and adapted to straddle the projecting lip of the shoe on the opposite side thereof, said base plate having an elongated slot extending in a direction transverse to a line joining the clamping hooks of said first pair, and a member for fastening said clamping hook unit and passing through said slot to permit said unit to slide adjustably along said base plate towards and away from said first pair of clamping hooks and to rotate adjustably about the axis of said fastening member, to accommodate the support device to shoes of varying size and shape.

2. A support device for a display figure having lower portions simulating human legs and feet, comprising a base plate in the form of a T having a substantially oblong stem section adapted in operative position of the device to extend along the bottom of the foot and to project at its outer end beyond the heel of the foot, and a cross-head section adapted to extend at opposite ends beyond the sides of the foot, the projectable ends of said base plate sections being provided with holes to receive floor fastening means, a pair of clamping arms integral with and extending from said crosshead plate section, said clamping arms terminating in respective hooks adapted to catch on to the sole part of the foot on one side thereof, a second pair of clamping arms secured together as a unit and extending from said crosshead plate section, said latter arms terminating in respective hooks adapted to catch on to the sole part of the foot on the opposite side thereof, and an elongated slot and screw connection between said second pair of clamping arms and said crosshead plate section permitting said second pair of

clamping arms to be adjusted along said cross-head plate section and about the axis of the screw.

3. A support device for a display figure having lower portions simulating human legs and feet and fitted with shoes, comprising a base plate adapted to extend along the underside of a shoe, at least one clamping hook rigid with said base plate and adapted to engage over the edge of the sole of the shoe on one side thereof, a V-shape member having a hook on the end of each leg, the base plate having a transverse slot therein, and a screw having its shank in the slot and engaging the bottom of the V-shape member and having its head bearing on the bottom of the base plate, the V-shape member being disposed with its arms directed toward the opposite edge of the sole, whereby the V-shape member is bodily adjustable in the slot and is rotatably adjustable on the screw as an axis and the hooks on the ends of its arms come to cause to engage over the opposite edge of the sole.

4. A support device as defined in claim 3 in which the arms of the V-shape member are of unequal length.

5. A supporting device for a display figure having lower portions simulating human legs and feet, comprising a base plate securable to a supporting surface and including a portion adapted to receive the sole of a foot of a figure, said portion having a transversely extending slot therein, a clamping hook integral with one side of the plate and adapted to engage over the edge of a shoe sole on the foot on its side, a V-shape member having a hook on the end of each leg adapted to engage over said sole on the other side, and an adjustment screw depending from the V-shape member and engaging in the slot and adapted to secure the V-shape member in adjusted position along the slot, said member being free for rotative adjustment on said screw.
